UNITED STATES PATENT OFFICE.

CLAIBORNE WATTS GOOCH, JR., OF LYNCHBURG, VIRGINIA, ASSIGNOR TO UNITED CIGARETTE MACHINE CO. INC., OF LYNCHBURG, VIRGINIA, A CORPORATION OF VIRGINIA.

CONSTANT-LEVEL HOPPER FOR TOBACCO-FEEDING MACHINES.

Application filed September 9, 1926. Serial No. 134,352.

The object of the present invention is to provide means for maintaining a constant level of tobacco relatively to the feed rolls of a tobacco feeding machine, as well as maintaining the pressure of the tobacco against the feed rolls.

The invention will be understood by reference to the accompanying drawings, in which—

10 Figure 1 is a side elevation, partly in section, of an embodiment of the invention,

Figure 2 is a detail view of the pawl mechanism, and

Figure 3 is a detail view of the pointed rod device which is employed to support the tobacco when the movable panel of the hopper is returned to initial position prior to refilling the hopper.

In Figure 1 is shown an embodiment of the invention, somewhat diagrammatically. The hopper is indicated at A, into which the tobacco is placed periodically by an attendant the hopper being closed at the bottom by a belt, 1, at the rear by a movable panel, 2, at the front by the upper feed roll 3 and the lower roll 3*, and at the sides by spaced panels.

The feed rolls 3 and 3* are covered, as customarily, with card clothing. They rotate, as indicated by the arrow, and draw tobacco from the supply. Lower roll 3* has coarse teeth which become filled with tobacco, while upper roll 3 has fine teeth which serve to level the tobacco carried under it by roll 3*. The tobacco carried by the latter roll passes under the usual comb 4, having fingers or teeth which hold the tobacco in place.

40 A picker roll 5 removes the tobacco from roll 3^x, and fan 6 revolves to scatter the tobacco onto belt 7 which carries it to the cigarette making machine.

In order to keep a uniform height of tobacco and uniform pressure against the feed rolls, I employ the following instruments:

The rear panel 2 of the hopper is movable in the direction of the feed rolls, and as the tobacco supply diminishes the panel is brought nearer to the feed rolls, thereby decreasing the capacity of the hopper, keeping the tobacco at a constant level. At the top of the panel and fixed thereto is a rack 8, the rack projecting toward and above the feed

rolls, the rack being slideable relatively to a supporting member held by standard 9 of framework B, as for example the boss 9x.

Driven by sprocket wheel 10 through chain 11 is a second sprocket wheel 12 on shaft 13 which shaft is adapted to rotate a cam 14. Above shaft 13 and supported in bearing 15 is a shaft 16 upon which is fixed a cam lever 17 having at its end a contact roller 17^x which rests upon the periphery of cam 14. Thus during the rotation of cam 14 shaft 16 is oscillated. 65 60

Fixed upon shaft 16 and projecting upwardly is a lever 18 to which is pivotally connected a pawl 19 having a stud 19* adapted to engage the teeth of rack 8.

Fixed upon shaft 16 is the rear end of a register lever 20 having a depending end 20^x. In practice shaft 16 may have spaced register levers connected thereto and their ends connected by register bar indicated at 21, Figure 1. The register lever will be of sufficient weight to control the position of cam lever 17 relatively to cam 14. If the tobacco in hopper A is at a high level, cam lever 17 will be held at a high point relatively to the cam 14 so that the cam will have little action there- 80

14 so that the cam will have little action there-
on, whereas when the level of tobacco falls
to a predetermined point cam lever 17 will
be caused to drop such a distance relatively
to the cam that the latter may impart a sub-
stantial movement to the cam lever. As cam
lever 17 drops to its low point, shaft 16 is
rotated and pawl 19 advanced until stud 19^x
passes one tooth and falls into position. Thus
when the high point of the cam acts upon the
cam lever, the direction of rotation of shaft
16 is reversed and the rack is advanced a
distance equivalent to one tooth. If de-
sired, a rack such as 8 and operating means
therefor may be placed at each side of the
hopper, instead of at a single point. As rack
8 is moved rearwardly a latch pawl 22 catches
a new tooth and holds the rack in its ad-
vanced position.

The operation of the mechanism as a whole is as follows: As the feed rolls revolve cam 14, rotated by sprockets 10 and 12 and chain 11, raises cam lever 17 with each revolution thus oscillating pivoted shaft 16 and raising register lever 20, which falls of its own weight (and rocks shaft 16 accordingly) as cam lever 17 follows the low points of the cam. As

register lever 20 falls, arm 18 is rocked forwardly and carries pawl 19 along rack 8 which is held by latch pawl 22. The register lever falls until it rests on top of the 5 tobacco supply and if the tobacco level be below a predetermined point pawl 19 will be advanced far enough to catch the next tooth in rack 8. On the upward stroke of cam lever 17 pawl 19 advances rack 8 and with 10 it panel 2 toward the feed rolls 3 and 3^x, latch pawl 22 passes a new tooth and holds the rack in its advanced position. The advancing of the panel continues until the surface of the tobacco reaches a point where 15 register lever 20 cannot fall a sufficient distance to permit pawl 19 to engage the next tooth on the rack 8. Thus the level of the tobacco is kept approximately at any desired height from the time the hopper has been 20 freshly filled with tobacco and panel 2 is in its rear position, until the greater part of the tobacco is exhausted and panel 2 is in its forward position as indicated by dotted lines *a*.

25 When it is desired to refill the hopper the pawls 19 and 22 are disengaged from the rack and the panel returned to its initial position. To prevent the unsupported tobacco from falling away from the feed rolls when the 30 hopper is being charged pointed rods may be inserted through the side of the hopper, holes 23 being provided for this purpose. The rods 24 may be carried by a hand-frame 25 for convenient manipulation.

35 A different function of the mechanism may be obtained by different relative setting of the pawls. If the pawl lever 18 is set so as to give the pawl 19 a movement of more than one or nearly two ratchet teeth it will pick up 40 the rack on each up stroke and release it at the same point on the drop stroke thereby imparting a slow forward and back movement to the panel 8. This squeezing movement is of value and may be used to help break up 45 pockets or holes that often form in the mass of tobacco and cause irregular feeding.

Having described my invention what I claim and desire to secure by Letters Patent, is as follows:

50 1. In a device of the character described,

a chamber adapted to contain tobacco, a registering device the position of which is determined by the quantity of the tobacco in said chamber, and a movable member and actuating means therefor controlled by said registering device for decreasing the effective area of said chamber when the registering device reaches a predetermined position. 55

2. In a device of the character described, a chamber adapted to contain tobacco, a registering device the position of which is determined by the level of the tobacco in said chamber, and means controlled by said registering device for periodically compensating for reduced level through tobacco fed out of 60 the chamber, by increasing the level. 65

3. In a device of the character described, a chamber adapted to contain tobacco, means for feeding tobacco out of said chamber, and means for automatically reducing the area of the chamber during said feeding action, including a movable wall, power driven members for actuating said wall, and means regulated by the level of the tobacco in the 70 chamber for controlling the action of said power driven members on the wall. 75

4. In a device of the character described, a chamber adapted to contain tobacco, feeding rolls, a movable wall in said chamber, a rack connected to said wall, a pawl adapted to engage said rack, a cam device for actuating said pawl, and a registering device adapted to control the pawl in such manner that it becomes effective to move the rack when the level of tobacco in said chamber reaches 80 85 a predetermined position.

5. In a device of the character described, a chamber adapted to contain tobacco, feeding rolls, a cam device, an oscillatory shaft, a lever on the shaft and engaged by the cam 90 device, a pawl on the shaft, a rack engaged by the pawl, a wall connected to the rack, and a registering device on the shaft and the position of which is controlled by the tobacco level, said registering device adapted to hold the pawl lever in idle position until the tobacco level reaches a predetermined position. 95

In testimony whereof, I have signed my name to this specification.

CLAIBORNE WATTS GOOCH, JR.
